Des. 208,459
Patented Sept. 5, 1967

208,459

BEEF JERKY DRIER

Gene C. Rosholt, 251 Beloit Ave.,
Los Angeles, Calif. 90049

Filed Nov. 10, 1966, Ser. No. 4,609

Term of patent 14 years

(Cl. D11—1)

FIG. 1 is a top plan view of the beef jerky drier;
FIG. 2 is an elevational front view of the beef jerky
drier;

FIG. 3 is an end view of the drier;
FIG. 4 is an end view of the opposite end of the drier;
and

FIG. 5 is a perspective view of the beef jerky drier of
FIGS. 1 through 4.

I claim:

The ornamental design for a beef jerky drier, as shown.
